UNITED STATES PATENT OFFICE.

WILLIAM H. WADE, OF CHICAGO, ILLINOIS.

RADIO APPARATUS CABINET.

Application filed January 10, 1924. Serial No. 685,340.

To all whom it may concern:

Be it known that I, WILLIAM H. WADE, a citizen of the United States, and resident of Chicago, Cook County, Illinois, have invented a certain new and useful Improvement in Radio Apparatus Cabinets, of which the following is a specification.

This invention relates to cabinets for radio apparatus, and more particularly to those for mounting and inclosing the receiving apparatus.

Generally stated, the object of the invention is to provide a novel construction and arrangement whereby the entire apparatus is built within and inclosed by a cabinet like structure whereby the batteries and the tuning devices, as well as the receiver and the amplifier therefor, are inclosed in fixed position in a cabinet which is a unitary structure, and which is attractive in appearance.

It is also an object to provide certain details and features of construction and combinations tending to increase the general efficiency and the desirability of a radio apparatus cabinet of this particular character.

To the foregoing and other useful ends the invention consists in matters hereinafter set forth and claimed and shown in the accompanying drawings in which—

Figure 1 is a front elevation of a radio apparatus cabinet embodying the principles of the invention, showing one of the front doors thereof in open position, and showing the other door closed.

Figure 2 is a vertical section on line 2—2 in Figure 1.

Figure 3 is a horizontal section on line 3—3 in Figure 2.

As thus illustrated, the invention comprises a cabinet having upright sides 1, a bottom 2, shelves 3 and 4, and a top 5, all combined in a manner to form a rectangular cabinet structure. With this construction, it will be seen, there are three compartments 6, 7 and 8, one above the other, and in order that these compartments may be supported in suitably elevated position, the bottom 2 is provided with legs 9 which stand on the floor. The lower compartment 8 has a front wall 10 which is preferably fixed in position, so that this compartment is only accessible at the back thereof. The compartment 7 has an inclined front wall 11, set in a distance from the front of the cabinet, which forms the front panel for the

radio tuning devices, and adjuncts, as indicated in the drawings. This front panel 11, with the apparatus thereon, is removable from the front of the cabinet, but the rear end of this compartment may be left open 60 to afford access thereto, and to the apparatus therein. The compartment 6, which is at the top of the cabinet, and which may be of less height than the other compartments, as shown, contains the telephonic receiving 65 instrument 12, which latter is mounted on the end of the amplifier or resonator 13, whereby the sounds produced by the receiving instrument 12 are amplified in a satisfactory manner, not by a portable horn or 70 amplifier which stands on top of the cabinet or which is a separate unitary piece of apparatus, but by an amplifier which is built into the cabinet and which is, therefore, rigid with the front tuning panel 11 of the 75 radio apparatus. In other words, the amplifier 13 supports the receiver 12 in stationary and fixed position, and this amplifier is built into the cabinet which forms an attractive piece of furniture, and which 80 contains the other apparatus, including the batteries shown in the lower compartment 8, whereby the cabinet and the radio apparatus form a unitary structure which can be moved around and placed in any desired 85 position like an ordinary piece of furniture. The front panel 11, which carries the various devices common to apparatus of this kind, is preferably inserted at the front of the cabinet, as stated, and may be removably held in place by screws 14 inserted through the panel and into the cleats 15 provided on the side walls of the cabinet. As shown in the drawings, the shelf 4 is cut away at 16, so that the sound vibrations may escape 90 from the mouth of the amplifier in a downward direction, the upper portion of the amplifier overhanging this wide notch 16, as it may be called, so that the space 17 at the front of the compartment 7, in front of the 100 panel 11, to a certain extent forms a part of the resonating or amplifying chamber. Doors 18 are provided for the front of the cabinet, hinged at 19 on the front edges of the side walls 1 of the cabinet. When closed 105 these doors entirely conceal the resonator and the front panel 11 and the front wall 10, and keep the dust out. It is also contemplated that doors may be provided for the back of the cabinet, so that when closed 110

at the front and back the cabinet will be practically dust tight, thus keeping the apparatus in good condition.

Thus the invention comprises a cabinet which is of a convenient size and attractive appearance and which, when closed, gives no suggestion of what it contains, or of its purpose, but which to the contrary, so far as external appearance is concerned, might 5 be a cabinet for ordinary purposes. This avoids the use of a portable horn or amplifier, and substitutes therefor an amplifier or resonator which is combined with the other apparatus in a unitary cabinet like 10 structure, and which is built into the cabinet and made a permanent portion thereof. The receiving instrument or reproducer is supported by the amplifier, in fixed position, and is combined with the other elements 15 of the apparatus in a unitary structure, so that the instrument 12 and the amplifier 13 are rigid with the front tuning panel 11 of the apparatus. At the same time, however, all of the elements of the 20 apparatus are easily accessible for the purpose of inspection or repair or adjustment, when such is necessary or desirable.

It will be understood, of course, that the amplifier or resonator 13 can be made of 25 wood or fiber or metal or any suitable material. The receiving or reproducing instrument 12 is preferably removably mounted on the inner end of the resonator, and in order to increase the length of the resonator 30 its inner end portion is preferably bent around and curved off toward one side of the cabinet, in the manner shown. The front edge portion of the lower wall of the resonator is, of course, cut away to correspond 35 with the shape of the wide notch 16 formed in the front edge of the shelf 4, whereby the space 17 communicates at its top with the interior of the resonator, thereby forming a resonating chamber at 40 the front of the cabinet. Obviously, a grille work of some kind, not shown, can be employed across the front or mouth of the resonator, if this is desired. Everything 45 is easily accessible at the back of the cabinet, whether the back is left open or provided with doors, and the front doors of the cabinet when closed conceal the nature 50 and purpose of the cabinet.

Thus a resonator or sound amplifier is 55 provided, and a rigid housing structure is combined with this resonator, so that the resonator is built into the housing, and whereby the housing and resonator together 60 form a resonating structure having a fixed resonating chamber therein. Then means are provided for supporting the front tuning panel of the radio apparatus within the front portion of said resonating structure, so that the housing that forms a part of

said structure will also enclose the radio 65 front panel and the apparatus associated therewith. The telephonic instrument or the receiving instrument of the resonator is supported entirely by the inner end of the resonator, inasmuch as it is the outer or 70 larger front end of the resonator which is rigidly attached to the structure forming the cabinet.

As shown and described, the outer surface of the front tuning panel 11 is in position 75 to reflect the sound outwardly, as the chamber in front of this panel is in communication with the interior of the resonator, and the doors 18 can be used to modulate the sound, of course, by partially closing the 80 doors in a manner that will be readily understood.

What I claim as my invention is:—

1. Radio apparatus comprising a resonator, a telephonic receiver for said resonator, rigid therewith, a radio front tuning panel, means forming a chamber for said resonator and telephonic instrument, the resonator being rigidly mounted therein, means forming a chamber back of said tuning panel, and instrumentalities co-operating with both of said means to form a cabinet-like structure in which one chamber is disposed in fixed relation to the other, whereby said apparatus is combined in one unitary structure in which the resonator is fully enclosed, having a cabinet-like exterior, said tuning panel being set into the cabinet a distance, to provide a space in front of said tuning panel, which space communicates with the interior of the resonator, so that the front of the tuning panel will reflect the sound outwardly.

2. Radio apparatus comprising a resonator, a telephonic receiver for said resonator, rigid therewith, a radio front tuning panel, means forming a chamber for said resonator and telephonic instrument, the resonator being rigidly mounted therein,

means forming a chamber back of said tuning panel, and instrumentalities co-operating with both of said means to form a cabinet-like structure in which one chamber is disposed in fixed relation to the other, whereby said apparatus is combined in one unitary structure in which the resonator is fully enclosed, having a cabinet-like exterior, said tuning panel being set into the cabinet a distance, to provide a space in front of said tuning panel, which space communicates with the interior of the resonator, so that the front of the tuning panel will reflect the sound outwardly, said cabinet having doors common to said resonator and the space in front of the tuning panel for enclosing the entire front of the panel and for modulating the sound.

WM. H. WADE.
